UNITED STATES PATENT OFFICE.

JAMES E. SHAPLEY, OF BINGHAMTON, NEW YORK, ASSIGNOR OF ONE-HALF TO WILLIAM M. SHAPLEY, OF SAME PLACE.

STEAM-GENERATOR.

SPECIFICATION forming part of Letters Patent No. 320,446, dated June 16, 1885.

Application filed August 4, 1884. (No model.)

To all whom it may concern:

Be it known that I, JAMES E. SHAPLEY, of Binghamton, county of Broome, State of New York, have invented an Improvement in 5 Steam-Generators, of which the following description, in connection with the accompanying drawings, is a specification, like letters on the drawings representing like parts.

My invention relating to steam-generators, 10 especially intended to be used in connection with small or portable engines, is intended as an improvement on the generator or boiler shown in Letters Patent No. 147,437, dated February 10, 1874, to which reference may be had. The said patent showed a steam-generator having a conical fire-box inclosed within 15 a boiler, and having lateral flues near the top of the fire-box opening into an annular chamber, from which descending flues pass through 20 the water-space at the side of the fire box into an annular flue at the base of the boiler surrounding the ash-pit, from which annular flue the products of combustion were led to a suitable stack or chimney.

25 The present invention consists in a generator constructed substantially like that shown in the said patent, combined with an outer shell or casing inclosing the entire generator, and having a stack or chimney at its upper 30 end, so that the products of combustion passing down through the descending flues, instead of being discharged directly into a chimney leading from the lower end of the boiler, pass upward again within the jacket 35 and around the boiler, imparting additional heat thereto.

The invention further consists in various 40 details of construction, by which the flues and boiler are rendered easily accessible for the purposes of cleaning.

Figure 1 is a front elevation of a steam-generator embodying this invention; Fig. 2, a vertical section thereof, and Fig. 3 a detail to be referred to.

45 The entire apparatus is shown as supported on a base, *a*, which may be of cast-iron, having an annular rib, *a'*, which receives the end of the shell *b*, containing the grate *c*, and constituting the fire-box or combustion-chamber 50 of the furnace. The portion of the shell *b* below the grate is shown as cylindrical, and

constitutes the ash-pit, which is accessible through the door *d*, Fig. 1, while the portion above the said grate is tapering or conical, as in the patent referred to, and is closed at its upper end by a crown-sheet, *e*. The fire-chamber is surrounded and inclosed by a shell, *f*, connected at its lower end by an annular piece, *f'*, with the shell *b*, and a short distance below the upper end of the shell *b*, connected 60 by an annular piece, *f*², with the lower end of a drum, *g*, surmounting the upper end of the fire-box. A tight chamber is thus formed between the plates *b*, *f*, *f'*, *f*², and *g*, which constitutes the boiler, the lower portion of which, 65 surrounding the said fire-chamber *b*, is to be filled with water, and the upper portion, *g*, forming a clear space or dome for steam.

The top plate, *g'*, of the drum or boiler and the crown-sheet *e* of the fire box are connected 70 by stay-bolts *h*. The plate *f*² constitutes a shoulder in the outside of the boiler, upon the outer edge of which is placed a ring, *i*, which may be of cast-iron, having a rabbet, *i'*, at its upper end, which receives the lower end 75 of a series of curved covers, *k*, the upper ends of which have a flange or projection engaged, and supported by a flange, *m*, upon the shell *g*.

The joints between the cover *k* and flange *m* and ring *i* may be ground so as to fit 80 tightly, and the said cover and ring inclose an annular flue or chamber surrounding the lower end of the drum *g* below the level of the crown-sheet *e* of the fire-box.

A series of short lateral flues, *n*, open from 85 the upper end of the fire-box into the said annular chamber, and a series of flues, *o*, passing from one to the other of the annular pieces *f*' *f*² through the water-space between the sheets *f* and *b*, connect the said annular chamber with the space below the boiler surrounding the ash-pit.

The apparatus thus far described is substantially like the corresponding parts in the patent referred to; but in the said patent the 95 vertical flues *o* opened into an annular flue surrounding the ash-pit, from which the products of combustion were conveyed without having further heating effect upon the boiler.

In the present invention the boiler and ash-pit are surrounded by a shell, *p* *p'* *p*², inclosing a space between it and the shells *f* *g*, and rest-

ing at its lower end upon the base *a*, which has a suitable groove or ledge to receive it. The shell *p* is cylindrical as far as the upper end of the shell *f*, and is surmounted by a 5 tapering or conical portion, *p'* *p*², inclosing the steam-dome *g*, and covered by a cap, *p*³, from which the stack or chimney *p*⁴ discharges the products of combustion. The upper portion, 10 *p*², of the outer shell, with the cap and stack, are supported by brackets *r*, connected with the sides of the dome *g*, and the portion *p'* is provided with handles *p*⁵, by which it may be raised upward or around the portion *p*² to afford access to the covers *k* of the annular 15 chamber communicating with the flues *n o*.

When in its lower or normal position, the portion *p'* of the outer shell or jacket is sustained by the portions *p* *p*², owing to the taper thereof, the said portion *p'* lapping over the 20 said portions *p* *p*² to make tight joints between them, and the portion *p*² is provided with holding devices (shown as spring-hooks *t*) for supporting the movable portion or cover *p'* when raised to afford access to the covers *k*, 25 and by removing the said covers to the flues *n* and *o*.

The outer shell, *p*, may be provided with openings *u*, affording access to the space surrounding the ash-pit for cleaning the same, 30 and the said shell is provided with funnel-shaped portions *w*, extending to the sides of the boiler around plugs *w'*, which thus afford access to the interior of the boiler for removing sediment or other purpose, the said plugs 35 thus being accessible from the outside of the apparatus without removing the outer shell or jacket.

The products of combustion from the fire-box pass through the flues *n o* into the lower 40 end of the outer shell or jacket, and thence up around the exterior of the boiler to the stack *p*⁴, from which they are discharged, and by thus surrounding the entire boiler with heated products of combustion a considerable 45 saving of fuel is effected.

I claim—

1. The fire-box, and boiler inclosing it having internal flues near the top of the fire-box, and the annular chamber surrounding the

boiler and communicating with said flues, and 50 having the curved covers *k*, for permitting access to the flues entering said chamber, combined with the flues extending downward from said chamber through the boiler at the side of the fire-box, and the jacket surrounding 55 the boiler, and provided with a movable section at or near its top, with a stack or chimney to discharge the products of combustion after having passed upward between the boiler and jacket, substantially as described. 60

2. The fire-box and boiler provided with flues, combined with the jacket surrounding the said boiler, having a movable section or cover, and holding devices for supporting the said cover in the position to afford access to 65 the flues, substantially as described.

3. The fire-box and boiler and annular chamber surrounding the boiler near the upper end of the fire-box, provided with removable covers, and flues communicating with the said 70 chamber, combined with the jacket surrounding the said boiler, having a removable portion or cover, affording access to the covers of the annular chamber, substantially as described.

4. The fire-box and boiler provided with flues, combined with the jacket surrounding the said boiler, composed of a cylindrical portion surrounding the lower portion of the boiler, a tapering portion surrounding the upper portion of the boiler and independently 80 supported therefrom, and a movable portion covering the space between the said upper and lower portions, substantially as described. 75

5. The fire-box and boiler provided with an opening near its lower end, and a jacket 85 surrounding the said boiler, combined with a plug closing the said opening of the boiler, accessible from the outside of the jacket, which is provided with a depressed portion surrounding the said plug, substantially as described. 90

In testimony whereof I have signed my name to this specification in the presence of two subscribing witnesses.

JAMES E. SHAPLEY.
